UNITED STATES PATENT OFFICE.

CHARLES JOSHUA LANE, OF LONDON, ENGLAND, ASSIGNOR TO CYRIL FRANK ELWELL,
OF LONDON, E. C. 1, ENGLAND.

FURNACE.

1,399,970.

Specification of Letters Patent. Patented Dec. 13, 1921.

Application filed August 6, 1920. Serial No. 401,769.

To all whom it may concern:

Be it known that I, CHARLES JOSHUA LANE, a subject of the King of England, residing at London, England, have invented 5 certain new and useful Improvements in Furnaces, of which the following is a specification.

This invention is for improvements in or relating to furnaces of the type used for 10 galvanizing or otherwise coating articles, and comprising a drum to receive the articles and the material wherewith they are to be coated, which drum is arranged to be rotated while it is heated externally to bring 15 it to the temperature required for the particular process that is being used.

According to the present invention there is provided in furnaces of the type described the combination with a long and 20 narrow horizontal combustion chamber, of a removable cover therefor, a rotatable drum supported within the chamber on half bearings, so as to be removable upward when the said cover is removed, and a series of 25 twyers spaced apart along a combustion chamber, said drum being interposed in the direct path from the twyers to the outlet flue from the combustion chamber.

Preferably the removable cover for the 30 combustion chamber is hinged to it along one side.

According to another feature of the invention the combustion chamber is substantially cylindrical, the twyers are disposed 35 in a line along the lowermost part thereof, and the rotatable drum is disposed eccentrically in the upper portion of the cylindrical chamber, such construction offering various advantages hereinafter set forth.

40 According to yet another feature of the invention the whole formation is constructed as a self-contained unit which comprises the combustion chamber, rotatable drum, driving gear for the drum, and a fan supplying 45 injector twyers and driven from said driving gear, all these parts being mounted on a framework and preferably arranged above ground level for the purpose hereinafter described.

50 In the accompanying drawings, which illustrate one embodiment of this invention,

Figure 1 is a front elevation of a complete furnace;

55 Fig. 2 is a plan of Fig. 1;

Fig. 3 is an end elevation looking from the right-hand side of Fig. 1, and Fig. 4 shows a detail.

Like reference characters indicate like parts throughout these drawings. 60

Referring to these drawings the complete furnace is mounted upon a suitable framework 10, which also comprises pillars or legs 11, whereby the various parts of the furnace are supported above the ground 65 level.

The furnace proper is constituted by a substantially cylindrical vessel 12, which is lined with fire-brick or other suitable heat-resisting and insulating material. The 70 upper half of this cylindrical chamber, as shown at 13 constitutes a lid for the lower half of the casing, being hinged thereto as at 14. Suitable handles are provided 75 at 15 on the ends of the cover or lid 13 to provide for conveniently opening and closing it.

The outlet passage from the combustion chamber 12 is provided by arched openings 16 toward the top of the rear wall thereof, 80 such openings communicating with a chamber 17 which is in direct communication with the outlet flues 18. These flues may be provided with dampers 19 in the usual manner. A door 20 is provided in the end wall 85 of the chamber 17 so that the said chamber can be easily cleaned or cleared.

The cylindrical combustion chamber 12 is provided in its end walls with semi-cylindrical bearings 21 constituting the lower 90 half of an ordinary bearing to support a rotatable drum 22 mounted on them. This drum is used to contain the articles which are to be coated while they are being heat-treated. 95

In order to provide for the rotation of the drum 22 at a suitably low speed, a worm driving gear is mounted on the framework 10 at one end of the furnace 12. The drive is conveniently taken through fast-and-loose pulleys 23, 24 which are mounted on a counter-shaft 25, and a worm on the end of the shaft, within the casing 26 (see Fig. 3) engages a worm-wheel in a casing 27. The shaft for this worm-wheel is shown as 105 28 in Fig. 2, and any convenient means may be used for coupling the shaft of the worm-wheel to the trunnion-shafts of the drum 22. In the construction illustrated, the said trunnion-shaft 29 is provided with a diam- 110

etral slot 30, and the worm-wheel shaft 28 is provided with a similar slot 31 which is however of greater axial length. A key or dog 32 of suitable rectangular section to fit these slots 30, 31 is mounted on an endwise movable rod 52 which projects from the outer end of the worm-wheel shaft 28 and is fitted with any suitable striking device 33 whereby the key 32 may be moved into the position shown in Fig. 2, to couple the shafts 28 and 29 together, or may be withdrawn into the slot 31 and thereby free the shaft 29 of the drum.

In order to make the whole furnace a completely self-contained unit, there is provided a fan or blower 40, this being conveniently located on the framework 10 underneath one end of the chamber 17. The fan is driven by a belt 41 from the counter-shaft 25 above mentioned, and it supplies air under the necessary pressure through a pipe 42 to a delivery pipe 43 located underneath the combustion chamber 12 and extending throughout the length of that chamber. In order to insure a uniform delivery of air to the pipe 43, the pipe 42 is connected to it at the middle of its length. A series of branches 44 on the upper side of the pipe 43 supply air to nozzles entering or located within the combustion chamber 12. The construction of each of these nozzles is shown in Fig. 4 which is a sectional view of a nozzle with some parts broken away.

Each of the pipes 44 has connected to it a nozzle 45, which nozzle is mounted within a suitably shaped tube 46 open at its lower end. As illustrated, the nozzle 45 is screwed into a central boss which is supported on radial ribs in the base of the tube 46. Air under pressure is delivered by the fan 40 through the open end of the nozzle 45 and it exercises an injector effect so as to draw in additional air from atmosphere through the lower end of the tube 46, all of such air then being delivered into the furnace.

In the operation of this furnace coke or other suitable fuel is fed into the combustion chamber 12 when the lid or cover 13 is open. The cover is then shut down and the fan set in operation to blow up the fire by means of the twyers 45, 46. Simultaneously the drum 22 is set in rotation, and this rotation with the heating is continued as long as desired. Provision may be made for testing the extent to which the coating operation has taken place by means of a test-rod similar to that described in our concurrent patent application Serial No. 401,768, filed August 6, 1920, such rod being inserted through the trunnion bearing 50 at one end of the drum 22.

When the process is completed the fan is stopped, and simultaneously the drum 22 is also stopped. The cover 13 is lifted, and when the clutch 32 is disengaged from the

drum trunnion 29, the drum can be lifted vertically out of its bearings 21. As above stated the framework 10, 11 is so arranged that all the parts of the furnace are above ground level and the reason for this is to permit the use of a portable crane for the lifting of the drum 22, the base of the crane being run in underneath the furnace. When the drum has been emptied and recharged, it is replaced in its bearings 21 and coupled up by the dog-clutch 32 to the worm gear and the process repeated.

It will be seen, particularly from Fig. 3, that the flue opening from the combustion chamber 12 is situated behind and above the drum axis, and that the drum is itself located in the direct path from the twyers to the outlet flues, being disposed eccentrically in the upper portion of the chamber 12. This insures that the hot gases are caused to circulate around the drum and insure its satisfactory heating.

Another advantage of this construction is that the cylindrical or long and narrow formation of the combustion chamber enables a comparatively small quantity of fuel to be used in it so that rapid heating can be effected. Moreover the cylindrical formation of the bottom of the combustion chamber insures complete combustion of the fuel since the combustion takes place mainly around the twyers, and the unburnt fuel all tends to fall into the hot region.

Another important advantage of the hereinbefore described construction is that the use of injector twyers permits the use of a fan or blower of smaller dimensions than would otherwise be the case, and in addition insures that the twyers themselves are not subjected to the risk of burning, since they are effectively air-cooled by the flow of air through them.

Finally it will be appreciated that the arrangement of the furnace whereby the drum is lifted vertically from it instead of being removed endwise through the end of the combustion chamber, is of considerable advantage in that the space required for a furnace of this type is reduced to a minimum.

It will be appreciated that various modifications may be made in the precise details of mechanical construction and that the invention is not limited to the specific embodiment hereinbefore described.

What I claim as my invention and desire to secure by Letters Patent is:

1. In a furnace for heat-treating material, the combination of a substantially cylindrical combustion chamber whereof the length is greater than the diameter, a hinged cover extending throughout the length of said chamber on the upper part thereof, a plurality of twyers spaced apart in a line along the lower part of said combustion chamber, a closed rotatable drum supported eccentrically

cally within the upper portion of said combustion chamber and means outside said combustion chamber adapted to be coupled to said drum to rotate it.

- 5 2. In a furnace for the heat-treatment of material, the combination of a self-supporting frame-work, a substantially cylindrical combustion chamber whereof the length is greater than the diameter mounted on said 10 framework, an outlet flue-chamber supported on said framework and communicating with the interior of the combustion chamber in the upper portion thereof, a plurality of twyrs disposed in a line along the lower 15 part of said combustion chamber, a hinged cover on the upper part of said combustion

chamber, half-bearings in the end wall of said combustion chamber, a closed rotatable drum supported in said half-bearings eccentrically in the upper portion of said combustion chamber in the direct path from said twyrs to said outlet, a worm reduction gear external to said combustion chamber for rotating said drum, said reduction gear being mounted on said framework, a fan mounted 25 on said framework, a pipe from the outlet of said fan to said twyrs mounted on said framework, means coupling said fan to said worm gear, and a pulley whereby a drive can be imparted to said fan and said worm gear. 30

In testimony whereof I affix my signature.

CHARLES JOSHUA LANE.
